CHAPEL TENT

Thomas I. Curtis, Columbus, Ohio

Application September 12, 1939, Serial No. 294,533

6 Claims. (Cl. 135—4)

This invention relates to tents or canopies generally, but has special reference to chapel tents such as are used for sheltering the attendants at funeral services in cemeteries.

5 It is an object of the invention to simplify structures of this type which may be readily set up, knocked down and transported.

A further object of the invention resides in the provision of a collapsible frame for a chapel tent, 10 in which the end assemblies comprise unitary structures which may be collapsed and in which certain of the parts are adjustable.

Another object of the invention consists in providing latches for securing the parts of the 15 end frames in collapsed or folded condition, such latches also serving as anchoring means for the canvas covering.

A further object of the invention resides in the provision of novel means for quickly securing the 20 ends of the stay rods or braces which connect the end assemblies.

Other objects and advantages of the invention will be apparent from the following description when taken in connection with the accompanying 25 drawings, in which,

Figure 1 is a perspective view of one of the smaller chapel tents embodying the present invention, parts of the canvas covering being broken away to disclose the frame construction.

30 Figures 2 and 3 are detail sectional views taken on lines 2—2 and 3—3 of Figure 1.

Figure 4 is a detail perspective view of a corner of the frame in assembled relation.

Figure 5 is a similar view showing one end of 35 one of the longitudinal braces about to be installed.

Figure 6 is a plan view of one of the end assemblies in collapsed condition ready for storage or transportation, and,

40 Figure 7 is a perspective view, reduced size, of the chapel tent erected and ready for use.

Referring to the drawings in more detail, the numeral 1 indicates the main body of the chapel tent, and numerals 2 and 3 indicate the side and 45 end extensions or awnings; it being understood of course that these extensions may be applied to both sides and ends of the main structure if desired.

The frame on which the canvas or other covering for the tent is mounted is formed primarily of 50 tubular elements and comprises front and rear end assemblies and means for supporting these assemblies in erect and spaced relation. One of these assemblies will now be described.

55 The posts or legs of the tent frame are formed

of tubes 10 which telescopically receive the ends of smaller tubes or rods 11. The base of each leg 10 is provided with a flanged socket 12, the flanges being apertured to receive pegs or stakes for anchoring the posts to the ground. The 5 rods 11 of the posts are preferably provided with a series of transverse apertures 13 adapted to receive pins 14 for locking the rod in various extended positions.

To the upper end of each post 10—11 a bracket 15 is pivoted, the bracket being provided with a stop 16 for engagement with the post so as to limit its outward pivotal movement. An arch comprising arcuate members 17 forms a part of each assembly. These arcuate members 17 are 15 pivotally connected to the brackets 15 and the adjacent ends of these members are pivotally connected to lateral extensions 18 of a socket member 19. The socket 19 is adjustably connected to an upright 20 by means of a set screw 21. 20

Rigidly connected to each bracket 15 is a beam section 22 extending at right angles to the bracket 15 and having its opposite end pivotally connected to an extension 23 formed on a socket member 24. The lower end of the upright 20 as well as 25 the socket member receiving it are provided with aligned apertures for receiving a pin 25 for locking these elements in set-up position.

Rotatably and slidably mounted on each beam section 22 is a ring or collar 26 provided with a 30 set screw 27 for locking it in position. These rings are each provided with a lug 28 adapted to be engaged by an eyelet in the canvas cover, and also with a hook or latch portion 29. The latches 29, as indicated in Figure 6, are caused to engage the posts 10 when the end assembly is in collapsed condition. To this end the set screws 27 are loosened and the latches are swung about the beam sections 22 so as to engage the posts 10, after which the set screws are secured. When 35 in this position it is also to be noted that notches 12' formed in the base members 12 of the posts engage about the sections 22 and 20 thus causing an interlocking of the parts.

The end assemblies folded and secured in the 45 manner described are conveniently arranged for storage or transportation and yet may be readily extended into set-up position by releasing the latches 29, swinging the parts to the positions shown in Figure 1, projecting the rod 20 upwardly 50 through its socket 24 and tightening up on the set screw 25.

For properly spacing the end frames just described and for supporting them in erect position side-poles 30 and a ridge-pole 31 are employed. 55

- The ends of the poles 30 (Figure 4) are provided with downwardly directed plates 32 and these plates are adapted to be seated in pockets 33 formed on the adjacent sides of brackets 15. 5 Likewise the ridge-pole 31 is provided with end plates or hooks 34 adapted to be positioned in pockets 35 formed on the adjacent sides of brackets 19. Set screws 36 are provided for releasably securing each of the plates or hooks within the 10 pockets 33 and 35.
- The side-poles 30 are provided with brace rods 37 which are pivoted to sleeves 38 secured to the rails 30 by set screws 39. The sleeves 38 have lugs 40 formed thereon to be engaged by eyelets 15 in the edges of the canvas covering for the frame. On its free end the brace rod 37 is provided with a hook 41 adapted to be received in an eye 42 mounted on a sleeve 43 on the post 11. This sleeve 43 is of sufficient size to slide over and 20 encompass the lower end 16 of the pivoted bracket 15 and thus serves as a clamp to secure the bracket against movement about its pivot. A set screw 44 provides the means for locking the sleeve 43 in clamping position.
- 25 For supporting the dome or roof of the tent arcuate rods 46 are provided in addition to the arcuate rods 17 which form a part of the end assemblies. These arcuate members 46 have their ends secured in socket members 47 and 48 on 30 the side and central rails respectively. The sockets are formed on sleeves mounted on the side and central rails and these sleeves are secured in position by set screws. The side rail sleeves are provided with lugs for receiving eyelets formed 35 on the canvas cover of the tent as was the case in connection with the sleeves of latches 29 and the sleeves of braces 31. Additional sleeves 49 provided with lugs and set screws for securing the canvas in position may be spaced along the 40 side rails as desired.
- In order that awnings or extension members 45 may be attached to the front and one or both sides of the tent proper supplemental frames may be attached to the main frame adjacent the top thereof. One of these supplemental frames is clearly indicated in Figure 1 and comprises a substantially U-shaped element 50 having its ends pivotally connected to eyebolts 51 fixed to the brackets 15. Socket members 52 are adjustably mounted on the posts 10-11 by set screws 53 and are adapted to receive the free ends of 55 braces 54 which are pivotally connected to the arms of the U-shaped frame. The front posts of the chapel tent may be provided with double sockets 55 adapted to receive braces from both the side and front extension frames. It will be apparent that these awnings may be adjusted to suit conditions by merely raising or lowering the socket members 52 and 55.
- 60 The operations necessary to the setting up of the tent frame have been fully described in connection with the description of the structural details and need not be repeated. It should be emphasized however that by reason of the unitary 65 end assemblies the frame structures can be easily

erected or collapsed and readily stored or transported from place to place without liability of loss of parts and with a minimum expenditure of time.

In accordance with the patent statutes I have 5 described what I now believe to be the preferred form of the invention but inasmuch as minor changes may be made in the details of construction without departing from the spirit of the invention it is intended that all such changes be 10 included within the scope of the appended claims.

What is claimed is:

1. In a tent frame structure a foldable end assembly comprising a foldable arch member, a foldable beam member, brackets to which the ends 15 of the arch and beam members are attached, supporting posts, and pivotal connections between the brackets and the upper ends of the posts.
2. In a tent frame structure a foldable end 20 assembly comprising a foldable arch member, a foldable beam member, brackets to which the ends of the arch and beam members are attached, supporting posts, pivotal connections between the upper ends of the posts and the brackets, and extensions on the brackets adapted to engage the surfaces of the posts when the assembly 25 is erected.
3. In a tent frame structure a foldable end assembly comprising a foldable arch member, a 30 foldable beam member, brackets to which the ends of the arch and beam members are attached, supporting posts, pivotal connections between the brackets and posts, extensions on the brackets adapted to engage the posts when the 35 assembly is erected, and clamps for locking the extensions to the posts.
4. In a tent frame structure a foldable end assembly comprising a foldable arch member, a 40 foldable beam member, brackets to which the ends of the arch and beam members are attached, supporting posts, pivotal connections between the brackets and the upper ends of the posts, and latches for locking the beam sections and posts in folded relation.
5. In a tent frame structure a foldable end assembly comprising a foldable arch member, a 45 foldable beam member, brackets to which the ends of the arch and beam members are attached, supporting posts, pivotal connections between the brackets and the upper ends of the 50 posts, and latches pivoted on the beam members and adapted to be interlocked with the posts when in folded position.
6. In a tent frame structure a foldable end 55 assembly comprising a foldable arch member, a foldable beam member, brackets to which the ends of the arch and beam members are attached, supporting posts, pivotal connections between the brackets and the upper ends of the 60 posts, latches pivoted on the beam members and adapted to be interlocked with the posts when in folded position, and lugs on said latches for engagement with a fabric top.

THOMAS I. CURTIS. 65
